UNITED STATES PATENT OFFICE.

CHARLES S. BURTON, OF OAK PARK, ILLINOIS, ASSIGNOR TO MELVILLE CLARK PIANO COMPANY, OF CHICAGO, ILLINOIS, A CORPORATION OF ILLINOIS.

COMBINED PIANO AND PHONOGRAPH.

1,300,244.

Specification of Letters Patent. Patented Apr. 15, 1919.

Original application filed January 29, 1917, Serial No. 145,037. Divided and this application filed August 3, 1917. Serial No. 184,203.

To all whom it may concern:

Be it known that I, CHARLES S. BURTON, a citizen of the United States, residing at Oak Park, in the county of Cook and State 5 of Illinois, have invented new and useful Improvements in Combined Pianos and Phonographs, of which the following is a specification, reference being had to the accompanying drawings, forming a part 10 thereof.

This application is a division of my application Serial No. 145,037, filed January 29, 1917.

The purpose of this invention is to provide an improved construction of a phonograph combined with a piano and contained within the casing thereof, and of the piano casing adapting it for such combination.

In the drawings:—

20 Figure 1 is a perspective view of a piano embodying this invention.

Fig. 2 is a front elevation of the phonograph mechanism contained in the piano case, showing certain parts of the piano case 25 and mechanism for the purpose of indicating the relative location of the phonograph in the case.

Fig. 3 is a vertical section at the line, 3—3, on Fig. 2.

30 The specific purpose of the construction shown in the drawing is to adapt a phonograph mechanism to be mounted in a piano case, and construct a piano case so that it may be so mounted, with the record carrier 35 and the record thereon, positioned within the space which is usually available in front of the hammer action, instead of as has heretofore been generally considered necessary, in such position that the record carrier and record stand in the wider space 40 available within the case above the hammer action. For the purpose of so positioning the record carrier and record, the mechanism is designed and constructed to have 45 the record carrier in an edgewise upstanding position, presenting the face of the record to the view of the listener standing in front of the piano.

The general construction of the phonograph mechanism and the means for rotating the record is not herein claimed and is 50 designed to be illustrated and described here only so far as necessary to present the particular features which are modified from

the usual construction in order to accomplish the purpose of the present invention. 55

The drawings show a piano case, 1, containing an automatic player action which is indicated by the tracker box, 2, with a tracker, 3, and with note sheet carrying 60 rolls, 4 and 5, therein. The roll operating mechanism is indicated by the outline of the frame thereof, shown at 6, at the right hand end of the tracker box. A shaft, 7, extending behind the tracker box is to be understood as connected with the train of the roll 65 operating mechanism. This shaft communicates power for actuating the record carrier of the phonograph mechanism which is carried in the space available in the piano 70 case at the left hand end of the tracker box of the automatic piano playing mechanism, and in front of the hammer action of the piano indicated by the hammer rest rail, 9, and hammers, 10, shown in the customary 75 position with respect to the other parts mentioned of the automatic or player piano. The feature which distinguishes the present invention is the location of the record carrier, 12, of the phonograph in an edgewise 80 upstanding position so as to expose the record thereon, facing forward, through the aperture, 14, formed in the front of the piano case for giving access to the phonograph. 14^a is a door for closing this opening, conveniently hinged at its lower edge 85 for swinging forward to open, and provided with means for holding it horizontal at open position so that it constitutes a shelf upon which the records may be temporarily 90 lodged when changing the records on the record carrier. This door is rendered ornamental by a symmetrically situated forward swell, 14^b, which serves the mechanical purpose of accommodating the sound box of the 95 phonograph in the cavity which results at the inner side from making the swell at the outer side. For mounting the record carrier in the upstanding position described 100 and supporting the carrier operating mechanism, a frame, 15, is provided mounted upon the foundation board, 1^a, (though this particular method of supporting it is not essential). The power communicating shaft, 7, extending behind the tracker box from the 105 note-sheet-operating motor train situated at the opposite end of the tracker box obtains bearing in this frame, 15, and carries upon

its left hand end a disk, 16, which rotates in frictional engagement with a friction pulley, 17, on the shaft, 18, also journaled in said frame, 15, and having the record carrier tablet, 12, mounted upon its forward upper end, said shaft, 18, being journaled in horizontal position in said frame, 15, extending therein fore-and-aft as clearly seen in Fig. 3. The drawings show means for 10 modifying the speed of rotation of the record carrier, and a jointed construction of the tone arm for permitting the sound box to be withdrawn from the record for the purpose of inserting and moving and adjusting the stylus and other detail features 15 of construction which are fully described in said parent application No. 145,037 and are not herein claimed and need not be described.

20 A horn or amplifier, 21, may be mounted fixedly in position by the horn bracket, 22, to which said horn or amplifier is secured at its smaller end, and the tone arm, 31, is pivoted to said smaller end of the horn or 25 amplifier by a swivel joint as seen at 19, Fig. 3. By locating the record carrier in upright position for playing, as described, there is rendered available for the horn or amplifier, 21, an adequate space behind the 30 upper part of said record carrier; and usually this position will be found to be above the hammer action, as seen in Fig. 3. The depth from front to rear of the space thus made available permits making the amplifier of adequate dimensions while it is still contained wholly within the case. When 35 thus located the horn or amplifier is preferably made with its discharge mouth opening upwardly, which gives good opportunity for discharge of the sound by swinging up the piano top board in the usual manner for free discharge of sound from the piano itself.

Upon considering the relation of the tone 40 arm and sound box to the upstanding record which results from making the record carrier upstanding as described, it will be seen that when the tone arm is pivoted to the smaller end of the horn mounted by the bracket, 22 in proper position to cause the sound box stylus to move across the record in a direction substantially radial thereto, as it should for proper reproduction at all 45 points of its path, the center of gravity of the tone arm and sound box, that is, of the structure which is mounted for pivotal movement about the axis of the swivel joint of the elbow to the smaller end of the horn or amplifier, will tend to assume a position 50 in the vertical fore-and-aft plane through said swivel axis, and therefore at every other position there will be a lateral pressure of the stylus in the groove of the record, due to gravity. Since this lateral pressure will 55 vary at all positions in the swing of the 60

sound box and stylus over the record, it will tend to vary the reproduction of the record at different parts, and will also tend to wear the groove on one side or the other, that is, to wear it unequally on the two sides; and 70 it will also make the stylus liable to jump from the groove and swing to the neutral position. To prevent these results it is necessary that a counter-balance should be provided for the tone arm and sound box 75 which cannot be provided in the manner which would be most obvious, namely, by having a weighted extension of the tone arm at the directly opposite side of its fulcrum from sound box, because the piano 80 case does not afford space for accommodating a counter-balance in that position, and it is necessary to find other means for counter-balancing which can be accommodated within the space available. For this purpose 85 there is provided a weighted arm, 40, pivoted at any convenient position where it can be accommodated and connected by a link, 41, with the tone arm, the pivotal connections of the link to the tone arm and 90 to the counterbalance arm being at equal distances from the pivots about which said counter-balance arm and tone arm respectively swing, so as to give the weight, 42, an angular movement about the fulcrum of 95 said arm, 40, equal to that of the tone arm about its fulcrum in the horn bracket, and in an arc reciprocally situated with respect to the arc through which said sound box, (or to be more exact, the center of gravity 100 of the tone arm and its load, namely, the sound box) moves in traversing the record.

In view of the upstanding position of the record, the sound box stylus will not be adequately held to the record by gravity; 105 and the necessary pressure is provided by a spring, 45, stretched from a point on the tone-arm member, 30, which is offset toward the plane of the record from the pivot of said member, 30, 31, said spring extending 110 through said member, 31, to the back or top of the elbow and secured thereto. The point of attachment of the spring to the tone-arm member, 30, is selected so that when the sound box is withdrawn from the record a 115 certain distance, the line of tension of the spring passes pivot axis of the arm, 30, to the arm, 31, and the spring will then react to withdraw the sound box from the record instead of holding it toward the record, and 120 will sustain it in a convenient position for inserting and removing the stylus and introducing a record behind the tone arm on the record carrier.

To prevent the record from accidentally 125 escaping from the center pin of the record carrier and to cause the record to be lodged against the record carrier with sufficient certainty to insure the frictional engagement between the two by which the record is 130

carried with the record carrier, said center-pin is split and the split ends are spread apart and made elastic so that they may be closed together to admit the record onto 5 the pin, which spreading again elastically prevents the escape of the record.

I claim:—

1. In combination with an upright piano comprising a record carrier tablet mounted 10 for rotation in playing within the piano case about a fore-and-aft extending axis, said carrier having its entire extent and path of rotation in the space forward of the vertical plane of the hammer action; said phonograph comprising an amplifier located behind the plane in which the carrier is rotated about said axis and behind the upper part of said carrier.
2. In the construction defined in claim 1 20 foregoing, the smaller end of the amplifier being extended out laterally with respect to the amplifier, and also laterally with respect to the carrier from behind the latter past the edge thereof, so as to open forwardly at a 25 point laterally beyond the range of the carrier, the tone arm being pivoted to said smaller forwardly-opening end, said tone arm extending thence in front of the record carrier, transversely of the axis of the carrier.
3. In the construction defined in claim 2 30 foregoing, said smaller and forwardly open end of the amplifier being at a level approximating the level of the upper edge of the carrier, and thereby relatively remotely 35 above the level of the fore-and-aft axis of the carrier, the tone arm being pendant from said end of the amplifier in a transverse vertical plane in front of the plane of rotation of the carrier.
4. In the construction defined in claim 1, the amplifier having the axis of its widening portion from the axis of the pivot of the tone arm thereto to the mouth, curved in a 45 vertical plane substantially parallel to the plane of the carrier's rotation behind the latter having its sound-discharge mouth opening upwardly.
5. In combination with an upright piano, 50 a phonograph having its record carrier in

the form of a tablet for carrying a flat or disk type of record, the same being mounted and contained within the piano case with said carrier at playing position occupying a space forward of the vertical plane of the 55 hammer action, the amplifier having its smaller end for connection with the sound arm located laterally adjacent to the upper part of the record carrier, the tone arm pivotally suspended from said smaller end of 60 the amplifier, and swinging in front of the record carrier for coöperation with the record carried thereon, to an arc whose chord is steeply inclined, and a counterbalance for said pendant tone arm and the sound box 65 thereon comprising a weighted lever arm fulcrumed and positioned for oscillating in the space behind the upper part of the record carrier, and operating connections from said counterbalance to the tone arm. 70

6. In the construction set out in the last claim foregoing, the amplifier being extended from its smaller end in the space behind the upper part of the record carrier and behind said counterbalance. 75

7. In the construction set out in claim 5, foregoing, the counterbalance comprising a lever having its fulcrum supported on the record carrier bearing, and extending upwardly from said fulcrum in the space behind the record carrier, and carrying a counter-balancing weight at its upper end. 80

8. In the construction set out in the last claim foregoing, the tone arm having a lever arm, and a link connecting said lever arm 85 with the counter-balance lever, the length of said tone arm lever arm from the axis of the tone arm to the link pivot being the same as the distance of the other link pivot from the fulcrum of the counter-balance 90 lever arm, and the length of the link being such that the divergences from vertical position of the tone arm and of the counter-balance arm are the same throughout the range of playing positions of the tone arm. 95

In testimony whereof, I have hereunto set my hand at Chicago, Illinois, this 28th day of July, 1917.

CHARLES S. BURTON.
